UNITED STATES PATENT OFFICE.

RICHARD LEUMANN, OF CHAILLY-SUR-LAUSANNE, SWITZERLAND.

APPARATUS FOR WRAPPING UP ARTICLES OF PARALLELEPIPED FORM.

1,378,694.

Specification of Letters Patent. Patented May 17, 1921.

Application filed October 29, 1919. Serial No. 334,290.

To all whom it may concern:

Be it known that I, RICHARD LEUMANN, a citizen of the Republic of Switzerland, residing at Chailly-sur-Lausanne, Villa "La Loex," Switzerland, have invented certain new and useful Improvements in Apparatus for Wrapping up Articles of Parallelepiped Form; and I do hereby declare the following to be a clear, full, and exact description of the invention, such as will enable others skilled in the art to which it appertains to make and use the same, reference being had to the accompanying drawings, and to letters or figures of reference marked thereon, which form a part of this specification.

This invention has reference to apparatus for wrapping up articles of parallelepiped form wherein by means of a folding member 20 provided for the formation of a closing flap, side flaps necessary for the formation of said flap are preliminarily folded with a common peak or point lying in the central plane of the article, the side flaps being 25 turned over afterward so as to overlap each other by passing them along guide surfaces. The characteristic feature of the improved method of wrapping consists in the fact that the peak or point is deflected from the 30 central plane and is turned over with one of the side flaps in the contrary direction to that in which the other side flap has been previously turned or folded over so as to cause it to bear against the article, whereby 35 the folding line, caused by folding over the peak or point is so selected that the joint forming the point or peak of the two side flaps, which are then bearing against the article and are brought into a plane and are 40 overlapping each other, is located approximately in the central plane of the article. The apparatus for carrying out the method is characterized by means for deflecting the point from the central plane toward that 45 side flap which is to be first folded over, and furthermore by means for folding the said side flaps in such wise that the two side flaps upon the folding over come into contact at one spot that is located approximately in the central plane, the arrangement 50 being such that both said means come into operation before the two side flaps folded over are pressed upon one another.

The accompanying drawings show apparatus suitable for carrying out the method

of wrapping according to the invention, in a constructional form by way of example.

Figure 1 shows a section of the apparatus on the line I—I of Fig. 3;

Fig. 2 shows on an enlarged scale a portion of Fig. 1;

Fig. 3 is a section on the line III—III of Fig. 1;

Figs. 4 and 5 show details upon a larger scale.

Fig. 6 is a section corresponding to the line VI—VI of Fig. 4.

Fig. 7 is a section corresponding to the line VII—VII of Fig. 4.

Fig. 8 is an end view looking in the direction of the arrow VIII of Fig. 4.

Figs. 9, 10 and 11 show details upon a larger scale, Figs. 9 and 10 being side views from the left and right respectively and Fig. 11 being a front elevation.

Figs. 12 to 15 are perspective views illustrating the different stages of the wrapping process.

Fig. 16 is an enlarged longitudinal sectional view of the channel 59.

Fig. 17 is a plan view showing the final folding surfaces 59^a of the channel 59.

Referring to the drawings, 80 (Fig. 3) designates a driving pulley mounted on a shaft 81. The latter drives by means of a toothed wheel gearing 82 a shaft 83 (Figs. 1 and 3) which drives, in its turn, a shaft 84 by means of a toothed wheel gearing 85 (Figs. 2, 3, 1). On the shaft 84 is fixed a disk 86 provided with a laterally projecting pin 87 adapted to drive a Maltese-cross 88 which is fixed to a shaft 1. Rigidly connected to the disk 86 is a disk 89 provided with a recess 90 and adapted to coöperate with the curved portions 91 of the Maltese-cross 88. On the shaft 1 is further fixed a toothed wheel 92 meshing with a toothed wheel 93 which in its turn meshes with a toothed wheel 94 mounted on a shaft 95. On the latter is also mounted a paper-feed 100 roller 96.

Upon the rotary shaft 1 there is also rigidly fixed a disk 2 formed with marginal incisions and provided with six symmetrically arranged fixed jaws 3. Guides 4 with parallel sliding surfaces are arranged upon the disk 2 in such a way that the rods 5 of plungers 6 can move therein to and fro in a radial direction. The disk 2 also carries pins 7 on which are mounted movable jaws 8

65

110

which are attached to double levers 9, 10 the arms 9 of which are so influenced by springs 11 that the jaws 8 constantly tend to approach the jaws 3, consequently the jaws 3 and 8 constitute six pairs of tongs or grippers.

12 (Fig. 1) is a roll on which paper intended for wrapping purposes is mounted and from which a band or strip of paper 13 passes over rollers 71, then between the roller 96 and a roller 97¹ and finally through guides 14 and 15. Said strip 13 is cut between the guides 14 and 15 by the shears 16, whereby at each operation a rectangular sheet of paper 17 (shown in Fig. 2 in dotted lines) is cut off, which bears upon the guide 18 and upon the adjustable stop 19.

The shears 16 are actuated by a mechanism of well known design comprising a disk 72 mounted on the shaft 83 and having a cam-groove 72¹ in which runs a roller 75 (Fig. 1) of a double armed lever 73, 73¹ pivotally mounted on a shaft 74. The arm 73¹ is operatively connected to two rods 75, 76, the one of which is connected at the other end to one leg of the shears 16, while the second rod is connected at its other end to the second leg of the shears 16.

20 is a cap with an opening 22 through which the article 21 to be wrapped up is introduced in a direction parallel to the axis of the shaft 1, from an endless member 97 passing over a roller 98 receiving its drive from the shaft 83 by means of a chain 99. 35 The introducing of the articles into the cap 20 is effected by a lever 100 pivotally mounted on a shaft 101 and carrying a roller 102 (Fig. 3) coöperating with a laterally protruding surface 103 of the cam-disk 72 in order to bring about its oscillation. Through the opening 22 an oscillating thrust arm 23 can pass into the interior of the cap 20 and beyond it close up to the tongs or grippers 3 8 located at the moment 40 in line with the cap 20. The arm 23 which is pivotally mounted on a shaft 104 carries a roller 105 running in a cam-groove 106 of a disk 107 which is fixed to the shaft 83 and which, upon its rotation, causes an oscillation of said arm 23.

24, 25 are upper guide rollers and 26 is a lower guide roller for the article to be wrapped. 27 is an arc shaped guide plate.

Mounted to rock about a fixed axis 28 is 55 a double lever 29, 30 one end of which carries an angle plate 31, while at the other end the lever is attached to an angle piece 32 which, in its turn, is articulated to a guide rod 33 moved up and down by an angle lever 60 108. To the latter is pivotally connected a rod 109 which at its other end is pivotally connected to the arm 23.

Mounted to rock on a second fixed axis 34 is a double lever 35, 36 which is attached at 65 one end to the guide rod 33 and at the other

end carries a fork-shaped folder 37 (Fig. 5). Each of the two prongs of the folder is of wedge shape and has adjacent to the flap face 39 two symmetrical converging surfaces 40 and 41 (Fig. 9), which meet together at the edges 38' and 38'', so that a nose 38 is formed. From the face 39 to the nose 38 the fork is rounded off and forms a small surface 38''', which faces toward the disk 2. The nose 38 which is farther removed from the plane of the disk 2 than the face 39, is furthermore so located that a perpendicular from the nose 38 upon the plane of the disk 2 does not impinge upon the disk 2 itself but upon its extension.

The arrangement is such that the nose 38 at the end of an oscillation stroke of the folder 37 lies in the central plane 48—48 (Fig. 14) of the article which at the moment is carried past the folder at this point.

80 A carrier 42 (Figs. 4, 6, 7, 8) has rigidly mounted thereon guide surfaces 43 and 44; two such carriers are provided with the guide surfaces at such a distance from each other that the tongs or grippers 3, 8 with the articles gripped by them can pass between the pair of guide surfaces 43, 44. The two guide surfaces 43, 44 are doubly bent and the guide surface 43 located nearest to the shaft 1 is inclined in relation to the other guide surface 44. The curve or bend of the two guide surfaces is composed of a curve which runs concentrically to the periphery of the disk 2 and of a curve which extends transversely to the said concentric curve. The inclination of the two guide surfaces 43, 44 in relation to each other is of a changing character, as may be seen from Figs. 4 and 7, the inclination being strongest at the point 46 and weakest at the point 47. The point 47 lies, like the point 46, in the central plane 48 of the article being wrapped but closer to the latter than the point 46. The decrease in inclination from the point 46 to the point 47 is not uniform, and the surface 43 is bent more strongly in a transverse direction to the periphery of the disk than the guide surface 44. The edge 45 of the guide surface 43 is throughout closer to the plane of the disk 2 than the edge 49 of the guide surface 44 which edge up to the point 50 is approximately parallel to the edge 43.

100 In this way there is formed between the two edges a gap 52 which, in the longitudinal direction, is approximately concentric to the axis of the shaft 1 and the cross-section of which is inclined to the central plane 48—48 of the article which plane upon the rotation of the disk 2 is always parallel to the axis of the shaft 1. The point 46, that is to say the commencement or mouth of the gap 52 lies, as may be seen from Fig. 5, somewhat beyond the end of the path of oscillation of the folder so that the noses of 110

the folder, as shown in Fig. 5, pass somewhat into the gap 52. From the points 47 and 51 the two edges 45 and 49 move apart from one another so that an enlargement 5 53 is produced, the edge of which is marked 55. The two guide surfaces 43 and 44 unite in a surface 54 confining a portion of the enlargement 53. The surface 54 is of approximately conical shape, as the edge 55 10 is farther removed from the article than the boundary line 56, at which the surface 54 passes over into the plane 57, which latter lies quite close to the article as the same travels past. The transition of the 15 guide surfaces 43 into the conic surface 54 takes place more abruptly than that of the guide surface 44, as the point 47 is situated closer to the article than the point 51.

58 is an oscillating arm and 59 is a guide. 20 The arm 58 is pivotally mounted on a stationary shaft 110 and it is linked to the angle lever 108 by means of a member 111, so that it is rocked upon an oscillation of the lever 23 which is rocked when the cam-disk 25 107 rotates.

The method of operation and working of the apparatus described is as follows:

The article moved into the gap 20 is pushed forward by the thrust arm 23 so 30 that it carries along the piece of paper 17 in which it is to be wrapped and, passing between the guide rollers 24, 25, 26, is pushed in between the cheeks or jaws 3 and 8 of the grippers. The size of the piece of 35 paper and the distance of the stop 19 from the feed aperture are such that the article is covered on three side surfaces by the paper while a portion of the latter extends beyond and hangs over the article and upon 40 the gripper which holds the article passing into the next position to do which it must move through an angle of 60°, which movement is effected by the intermittent partial rotation of the disk 2 brought about by the 45 parts 86, 87, 88, 89. The projecting length of the paper slides past the guide plate 27 and is folded over thereby; the folded end portion is then pushed by the angle plate 31 between the jaws 3, 8 and is caused to overlap 50 the other edge of the piece of paper.

Upon a further partial rotation of the disk 2 through an angle of 60°, the grippers 3, 8 pass into the position in which by means of the folder 37 the side flaps 61, 62 55 necessary for the formation of the closing flaps 60 (Figs. 14 and 15) and provided with a common peak or point 63 (Fig. 12) lying in the central plane 48—48 of the article are preliminarily folded. The preliminary 60 folding is effected through the folder 37 at the opposite sides of the article, swinging down upon the parts of the paper projecting laterally over the article, in the following manner: The dimensions of the article, 65 measured from the one central line 48 to

the other central line 48 (Fig. 14) corresponds approximately to the distances between the flat surfaces 39 of the two prongs of the folder 37, whereby a certain amount of play is provided between each flat surface 39 and the adjacent surface of the article. Each prong alters the parallelepiped form of the projecting portion of the pieces of paper into that shown in Fig. 12, as the flat surface 39 presses the upper flaps 70 of the paper upon the article and the nose 38 carries downward with it the lower flap 75 and bends it out thus forming the peak or point 63, while the two side flaps 61 and 62 bear upon the two surfaces 40 and 41. It 80 will be understood that upper and lower are terms with reference to Fig. 12. The surface 38'' at the same time permits a transition from the even surface of the flaps bearing upon the article to the point or 85 peak 63.

Fig. 5 shows the relative position of the folder 37, of the article and of the part 42, after the preliminary folding has been effected, it being duly observed that the folder 90 prong shown and the flaps 61 and 62 do not coöperate with the part 42 shown but with that lying opposite; in other words, it is assumed that the front portion 42 coöperating with the portions of the folder prong 95 shown in full lines has been removed. The nose 38 and consequently the peak 63 have hereby passed into the gap 52, at the point where it commences, and the flaps 61 and 62 lie partly upon the guide surfaces 43 and 100 44. The folder 37 then retires and when the grippers are moved farther forward, the peaks 63 lie to the front in the direction of movement. The arrangement is such that the guide surface 43 then comes first into 105 operation and commences to lay on to the article the lateral flap 62 lying against it. At the same time the peak enters into the gap 52; the edge 45 of the guide surface 43, which at the point 46 lies closer to the 110 axis 1 than the point of the peak, begins to gradually bend over the lateral flap 62 (Fig. 13), the deviation or deflection of the peak being thereby assisted in that the other lateral flap 61 begins to be folded over in a 115 direction contrary to that in which the side flap 62 is bent over by the guide surface 44. The side flap 62 is thus pressed more and more closely to the article by the guide surface 43 up to the point 47 where the edge 120 45 has bent into the sharply folded over peak a folding line 64 shown in Fig. 14, which figure shows the side flaps 61 and 62 after they have been folded one upon the other and after the flap 61 has been completely 125 folded over by the guide surface 44. The folding line 64, as it has been produced by the point 47 of the edge 45, runs in such wise that the point of intersection 66 of the line 64 with the folding line 65 (Fig. 14) of the 130

side flap 62 is located approximately in the central plane 48-48 of the article, as the point 47 of the edge 45 has come last in contact with the folding line 65.

5 Upon the further forward movement of the disk 2, the tip of the point or peak passes into the enlargement 53. The edge 55 is at a greater distance from the adjacent surface of the article 21 to be wrapped than the tip 10 of the peak. Consequently, upon the further forward movement of the article, the tip of the peak comes in contact with the surface 54 and by this latter is gradually conducted upon the plane 57. Now if the article itself 15 passes by the plane 57 closely adjoining it, then the two side flaps will be pressed firmly upon the article thus forming the folding line 67, and at the same time they are pressed flat.

20 The wrapping then appears as shown in Fig. 14 and in order to be given the final form shown in Fig. 15, all that is necessary is to fold the closing flap 60 over upon the ready wrapped article which is ejected into 25 the guide 59 out of the jaws through the oscillating arm 58 and plunger 6 at the next stopping point, which is situated diametrically opposite the point of introduction. The article is fed from said guide 59 further 30 forward gradually through the articles following on in order of succession. This folding over of the closing flaps 60 upon the article according to Fig. 15 is effected by means of oblique surfaces 59^a located at both sides 35 of the guide 59.

The advantage of the apparatus described consists in the fact that the closing flap can be made in a very neat manner. Hitherto this closing flap has been so made that the 40 preliminary folded covering shown in Fig. 12 is guided, in order to fold over the side flap, past inclined guide surfaces with the peak 63 turned toward the rear.

It will be clear that, without a prior folding over of the peak or point on one of the 45 two side flaps, which process has hitherto not been known at all, it is not possible to fold over in one and the same plane these two side flaps, which overlap at the top and 50 come into contact at the bottom in the form of a point or peak, without crushing or distorting this point. The folding over of the peak in a regular manner in such wise that the two side flaps retain a symmetrical appearance after overlapping, is furthermore 55 substantially facilitated by the fact that the leading peak in the very first place and then the side flaps, commencing from the peak to the rear, are subjected to treatment on the 60 part of the guide surfaces while, if the peaks on the contrary, in the manner so far practised, were to be brought in contact with the guide surfaces at the close, a folding over of the peak would be entirely out of the 65 question or would be very difficult.

What I claim now as my invention is:

1. An apparatus for wrapping articles of parallelepiped form, comprising means for gripping the article to be wrapped, means for moving the article to be wrapped against the wrapper, and then moving both article and wrapper into said gripper, means for stepping the gripper past a folding surface to bend the projecting edge of the wrapper at right angles, means for tucking the edge 70 of the wrapper into the gripper to overlap the opposite edge of the wrapper, end folding mechanism folding the ends into peaks at substantially the middle of the ends and means to fold the peaks over onto the back 75 80 of the package as it is discharged from the gripper.

2. An apparatus for wrapping articles of parallelepiped form, comprising means for gripping the article to be wrapped up, means for intermittently moving said first mentioned means together with the article, means adapted to wrap a piece of paper around the four longitudinal side surfaces of the article to be wrapped up partly before it is gripped 85 by the first mentioned means and partly while it is intermittently moved by said secondly mentioned means, a folder adapted to be moved relatively to the means gripping the article to be wrapped up, said folder 90 forming upon its movement two pairs of side flaps necessary for the formation of the closing flaps of the wrapper in such wise that said flaps are provided with a common peak lying in the central plane of the article, 95 means adapted to deflect upon a movement of the gripping means holding the article surrounded by the piece of paper, each peak from the central plane toward the side flap that has to be first turned over and fold the 100 side flaps such wise that the two side flaps of each closing flap are coming in contact upon their turning over by the last mentioned means at a point lying approximately in the central plane of the article, and means adapted 105 to fold the closing flaps over upon the ready wrapped article when the latter has been released by the means holding and advancing it during the wrapping operation. 110

3. An apparatus for wrapping articles of parallelepiped form, comprising means for gripping the article to be wrapped up, means for intermittently moving said first mentioned means together with the article, means adapted to wrap a piece of paper around the four longitudinal side surfaces of the article to be wrapped up partly before it is gripped 115 by the first mentioned means and partly while it is intermittently moved by said secondly mentioned means, a fork-shaped folder 120 adapted to be moved relatively to said means gripping the article to be wrapped up, two guide members, means operatively connected to the means for intermittently moving the gripping means and adapted to move the 125 130

folder and the gripping means, while they hold the article between the prongs of the folder, past said guide members, each of the latter comprising two curved guide surfaces 5 that are separated from each other by a gap inclined in cross-section to the central plane of the article, one of the curved guide surfaces of each of said two members coming first into action in that it immediately approaches the path corresponding to the plane of the side of the article which is moved past and begins to press one side flap of two side flaps formed by said folder at each side of the article toward the adjacent side of the latter, after which the other side flap is gradually laid over the said first mentioned side flap by the second guide surface which is removed farther from the said path, whereby an edge, formed by the first named guide surface and the adjacent wall of the gap is so formed that it bends-in the first named side flap at a point which lies approximately 70 in the central plane of the article, and means adapted to fold the two side flaps on each side of the article over upon the ready wrapped article when the latter has been released by the means gripping it during 75 the wrapping operation.

5. An apparatus for wrapping articles of parallelepiped form, comprising means for wrapping a piece of paper around the longitudinal side surfaces of the article, grippers for holding the article and the piece of paper wrapped around it, means adapted to intermittently rotate said grippers about a stationary axis, a pivotally mounted fork-shaped folder operatively connected to said means for rotating the grippers so that upon a rotation of the last mentioned grippers said folder is oscillated in the direction of rotation of the grippers, two guide members past which the pivotally mounted 85 folder and the rotatably mounted grippers are adapted to be moved, each of said guide members comprising two curved guide surfaces that are separated from each other by a gap inclined in cross-section to the central plane of the article, said gap and the edges of the guide members confining it being arranged concentrically to the axis about which the grippers can be rotated, and one of the curved guide surfaces of each of said 90 two members coming first into action in that it immediately approaches the path corresponding to the plane of the side of the article which is moved past and begins to press one side flap of two side flaps formed 95 by said folder at each side of the article toward the adjacent side of the latter, after which the other side flap is gradually laid over the said first mentioned side flap by the second guide surface which is removed 100 farther from the said path, whereby an edge, formed by the first named guide surface and the adjacent wall of the gap is so formed that it bends-in the first named side flap at a point which lies approximately 105 in the central plane of the article, and means adapted to fold the two side flaps on each side of the article over upon the ready wrapped article when the latter has been released by the means gripping it during 110 the wrapping operation.

4. An apparatus for wrapping articles of parallelepiped form, comprising means for gripping the article to be wrapped up, means for intermittently moving said first mentioned means together with the article, means adapted to wrap a piece of paper 115 around the four longitudinal side surfaces of the article to be wrapped up partly before it is gripped by the first mentioned means and partly while it is intermittently moved by said secondly mentioned means, a fork-shaped folder adapted to be oscillated relatively to said means gripping the article to be wrapped up, two guide members, means operatively connected to the means for intermittently moving the gripping 120 means and adapted to move the folder and the gripping means, while they hold the article between the prongs of the folder, past said guide members, each of the latter comprising two curved guide surfaces that are separated from each other by a gap inclined in cross-section to the central plane of the article and commencing somewhat before the point where the stroke of the folder ceases and terminating at a point 125 where the two curved guide surfaces of each member pass over into one single surface which latter surface gradually approaches the plane of the path of the article being moved past the same, one of the curved guide surfaces of each of said two members coming first into action in that it immediately approaches the path corresponding to the plane of the side of the article which is moved past and begins to 130 press one side flap of two side flaps formed

In testimony that I claim the foregoing as my invention, I have signed my name.

RICHARD LEUMANN.
